UNITED STATES PATENT OFFICE.

WILLIAM KERR EDGAR, OF LAWRENCE, KANSAS, ASSIGNOR TO THE EDGAR STEEL
SEAL & MFG. CO., OF LAWRENCE, KANSAS.

CAR SEAL.

Application filed July 22, 1921. Serial No. 486,819.

To all whom it may concern:

Be it known that I, WILLIAM KERR EDGAR, a citizen of the United States, residing at Lawrence, in the County of Douglas and

5 State of Kansas, have invented a new and useful Car Seal, of which the following is a specification.

This invention relates to car seals and is designed more especially as an improvement 10 upon the structure, shown, for example, in Patent No. 1,844,491 issued to me on June 22, 1920.

It is an object of this invention to provide a bendable strip of the interlocking 15 type shown in my patent mentioned, with a supplemental retaining tongue.

A further object is to provide a seal which will break when opened and which, if left in position after being opened or broken 20 will expose a portion of the seal not ordinarily visible and which portion is so distinctive in appearance as to readily attract the eye of the inspector.

Another object is to provide a seal which 25 by rearrangements is weakened at its bending point by transverse scores which can be produced easily and will not weaken the seal to the same extent as where perforations are punched into the seal.

30 With the foregoing and other objects in view which will appear as the description proceeds, the invention resides in the combination and arrangement of parts and in the details of construction hereinafter described and claimed, it being understood that, within the scope of what is claimed, changes in 35 the precise embodiment of the invention shown can be made without departing from the spirit of the invention.

40 In the accompanying drawings the preferred forms of the invention have been shown.

In said drawings—

Figure 1 is a perspective view of the seal.

45 Figure 2 is a perspective view showing the opposite side thereof and showing the supplemental holding tongue bent to its first position.

Figure 3 is a perspective view of the seal 50 and showing the end portions bent to interlocking position.

Figure 4 is a perspective view showing the seal completely folded or bent.

55 Figure 5 is a plan view of one end portion of a slightly modified form of seal.

Figure 6 is a perspective view showing the seal with its number end broken off.

Figure 7 is a view of a slightly modified form of seal.

Figure 8 is a perspective view showing 60 the first positions of the parts when said modified form is being bent to active position.

Figure 9 shows the modified form of seal 65 completely folded.

Figure 10 shows the seal after the number end thereof has been broken off.

Referring to the figures by characters of reference 1 designates an elongated strip of metal provided at one end with a T-shaped head 2 the neck of which is formed with an opening 3. The other end of the strip can be provided with a short tongue 4 although if preferred said end can be cut off straight. Formed in the strip 1 near that end from 70 which the tongue 4 extends are oppositely disposed T-shaped slots 5 and 6, the slot 6 being provided in the longitudinal portion thereof with a lug 7 so proportioned as to be insertible into the opening 3.

That portion of the strip between the slots 5 and 6 and the head 2 is divided into three portions by transverse scores indicated at 8 and 9. These scores may be extended straight across the strip as shown at 85 10 in Figure 5 or they can be arranged in pairs as in Figure 2, the scores of each pair being in alignment. That portion of the strip extending from the score 8 to the head 2 forms one end arm of the seal, indicated at 11 and on the scored side of the seal there is stamped in this end portion 11 suitable identifying data such as the initials or the name of the railroad on which the seal is used.

That portion of the sealing strip between the scores 8 and 9 and which has been indicated at 12 constitutes the body of the seal while that portion of the strip between the score 9 and the slot 6 forms the other end arm 13 of the seal. That end portion 90 of the strip between the slot 6 and the tongue 4 forms the locking portion of the seal, indicated at 14. This locking portion has the number of the seal stamped in that face thereof opposite to the face containing 95 the scores 8 and 9 and the designation 15.

One side edge of the end arm 13 is cut away to form a deep longitudinal recess 16, a portion of the metal cut away in the formation of this recess being retained to pro- 100 105 110

vide a narrow longitudinal tongue 17 normally extended toward the slot 6 as shown in Figure 1. In using this seal the tongue 17 is first bent back onto the scored face of 5 the strip 1 as shown in Figure 2. The strip is then inserted with its head 2 first through the part to which the seal is to be applied after which the arms 11 and 13 are bent at the scores 8 and 9. The prearrangement of 10 scoring causes the strip 1 to crack along these scores. This will permit the head 2 to be inserted into the slot 6 and onto the lug 7 after which the locking end 14 is bent back from the position shown in Figure 3 15 to the position shown in Figure 4, thus to bring the slot 5 around the head 2 thereby to lock the head on the lug 7 in the same manner as disclosed in my patent hereinbefore mentioned. The tongue 17 is then bent over 20 the free end of the locking portion 14 as shown in Figure 4 whereupon the sealing action is completed. With the parts thus arranged it will be noted that both the number of the seal and the name or designating 25 character appearing on the seal will be exposed to view.

In view of the prearrangement of the scoring at the bending points, the seal cannot be removed from the part engaged thereby 30 without first bending back the tongue 17. This bending of the tongue will release the number section, said section not necessarily breaking off. The locking end 14 must then be bent back to release the head 2 from the 35 lug 7 and this rebending will result in the severance of said locking means.

Furthermore it will expose to view the recess 16 so that when an inspector passes near 40 the seal he can detect at a glance whether the seal has been opened.

Importance is attached to the use of the scores 8 because they can be made very easily and eliminate the necessity of perforating the strip at the bending point. The 45 scores can be extended entirely across the strip as shown in Figure 5, if so desired, this arrangement preventing the strip from being folded backwards, inasmuch as any such attempt will result in the seal being 50 broken off at the score 5, 8 or 5, due to the fact that the proper cracking of the outer strata of the metal at the bending point is insured, the walls of the scores forming shoulders which serve to pry the seal apart 55 when bent in the wrong direction.

In Figure 6 the relative positions of the parts subsequent to the breaking off of the number end of the seal have been illustrated. Obviously after the number end has been 60 broken off the appearance of the seal will be quite different from what it was prior to the breaking off of the end of the seal and, therefore, the attention of the inspector will be promptly attracted to the seal.

65 In Figures 7, 8, 9 and 10 a slightly modi-

fied structure has been disclosed wherein the slot 18 is arranged oppositely to the slot 16 and is formed both in the middle section 12' and in the section 13'. Thus when the seal is given its first bend, as shown in Figure 8, the tongue 19 will extend beyond one of the angles. Consequently when the number end 20 is bent back to locking position its free end will rest on a portion of the tongue 19 and only one bend of said tongue will be necessary in order to bring it to holding position as shown in Figure 9. With this modified arrangement the tongue will be left outstanding when the number end 20 is removed, as shown in Figure 10.

What is claimed is:—

1. A car seal comprising a strip bendable at prearranged points and having interlocking portions, a locking end on the strip bendable to hold the interlocking portions 25 against separation, there being a recess in the seal having a portion normally concealed by said locking end when in holding position, and means bendable into engagement with the locking end while in holding position.

2. A car seal comprising a strip bendable at prearranged points and having interlocking portions, a locking end on the strip bendable to hold the interlocking portions 25 against separation, there being a recess in the seal having a portion normally concealed by said locking end when in holding position, and a tongue bendable from the recess into engagement with the locking end while 100 in holding position.

3. A car seal comprising a strip bendable at prearranged points, said strip having transverse scores at the bending points for weakening the strip, the said strip having interlocking portions, a locking end on the strip bendable to hold the interlocking portions against separation, there being a recess in the seal having a portion normally concealed by said locking end when in holding position, said strip being formed of a material adapted to separate when rebent at any point of bending.

4. A car seal comprising a strip bendable at prearranged points, said strip having transverse scores at the bending points for weakening the strip, the said strip having interlocking portions, a locking end on the strip bendable to hold the interlocking portions against separation, there being a recess in the seal having a portion normally concealed by said locking end when in holding position, said strip being formed of a material adapted to separate when rebent at any point of bending, and a tongue bendable from the recess into engagement with the locking end while in holding position.

5. A car seal comprising a strip bendable at prearranged points and having interlocking portions, a locking end on the strip 120

bendable to hold the interlocking portions against separation, and a tongue integral with the strip and bendable into engagement with the locking end, all portions of the strip being of a material adapted to break when rebent at any one point.

In testimony that I claim the foregoing

as my own, I have hereto affixed my signature in the presence of two witnesses.

WILLIAM KERR EDGAR.
